US00D427622S

United States Patent [19]

Conway

[11] Patent Number: Des. 427,622
[45] Date of Patent:  Jul. 4, 2000

[54] EYEWEAR

[75] Inventor: Simon M. Conway, Lima, N.Y.

[73] Assignee: Bausch & Lomb Incorporated,
Rochester, N.Y.

[] Term: 14 Years

[21] Appl. No.: 29/087,559

[22] Filed: May 5, 1998

[51] LOC (7) Cl. 16-06

[52] U.S. Cl. D16/326

[58] Field of Search D16/101, 300-330,
D16/335, 351/41, 44, 51, 52, 108; 2/447,
448
